UNITED STATES PATENT OFFICE.

EMIL BOJKO, OF MEACHAM, SASKATCHEWAN, CANADA.

TOOL.

1,284,575.

Specification of Letters Patent. Patented Nov. 12, 1918.

Application filed January 2, 1918. Serial No. 209,977.

To all whom it may concern:

Be it known that I, EMIL BOJKO, a subject of the King of England, residing at Meacham, in the Province of Saskatchewan and Dominion of Canada, have invented certain new and useful Improvements in Tools, of which the following is a specification.

This invention relates to tools and has special reference to a combined tool peculiarly adapted for use by railroad employees in loading trucks and in ballasting the same.

A first important object of the invention is to provide an improved device of this character having a pick and novel construction of pick point.

A second important object of the present invention is to provide a device of this character having an improved construction of a pick point.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a side elevation of the complete device with the extension point applied thereto.

Fig. 2 is a detail section through the head of the tool showing the manner in which the extension point is held in position.

Fig. 3 is a front view of the tool.

Fig. 4 is a detail view of the head of the tool showing how the two parts of the short pick lock together.

In the embodiment of the invention herein illustrated there is shown a tool which is provided with a head 10 having projecting from one side a hammer 11 and being provided on its forward face with a curved claw 12 which may be used for extracting spikes and the like. Projecting from the opposite side of the head 10 to the hammer 11 is a fixed pick point 13 which is preferably integral with the head. Adjacent the base of

the pick point 13 there is pivoted to the head a movable pick point member 14 which is provided near its point with a notch 15 arranged to receive a lug or projection 16 on the point 13. By this means, when the parts

are in the position shown in Fig. 4, the de-

vice may be used as a short pick as in handling ties and the like and the stresses due to such use will be taken by the lug and notch as well as the pivot 17. In order to hold the parts closed as in Fig. 4 there is 60 provided an L-shaped leaf spring 18 one end of which is fastened to the handle 19 of the tool while the other end is rolled as at 20 to fit a notch 21 on the rear face of the member 14. By this means the spring is kept 65 in position and also forces the parts 14 and 13 together. In order to lengthen the pick and to provide a tamping tool a removable pick point 22 is provided which has at its base portion a socket 23 fitting the member 70 14. Moreover this movable pick point is provided with a notch 24 wherein the lug 16 fits when the movable point is in use and with the notch 25 wherein the lug 20 of the spring fits, this being clearly shown in Fig. 75 2. Thus when the removable point 22 is in position it is locked to the member 14 by both the lug 16 and the spring 18 and at the same time the spring holds all of the parts in the position shown in Fig. 2. 80

It will be obvious that the removable point is to be used as in an ordinary pick for tamping the ballast under the rails and along the ties or for drawing out the ballast from beneath the rails. It will also be ob- 85 vious that the device, when arranged as in Fig. 4 may be used for driving spikes, extracting spikes, or handling the ties as is ordinarily done with the sharp pick point of the ordinary spike hammer. 90

There has thus been provided a simple and efficient device of the kind described and for the purpose specified.

It is obvious that many minor changes may be made in the form and construction 95 of the invention without departing from the material principles thereof. It is not therefore desired to confine the invention to the exact form herein shown and described but it is wished to include all such as properly come within the scope claimed.

Having thus described the invention, what is claimed as new, is:—

In a tool of the class described, a head 105 provided with a pick point consisting of a member fixed to the head and a second member pivoted to the head adjacent the base of the first member and provided adjacent its point with a notch in the face confronting the first member, a lug on the first 110

member entering said notch in the closed position of said members, said second member also having a notch in its rear face, a handle for said head, and an L-shaped leaf spring having one end fixed to the handle and the other end rolled to form a lug entering said second notch, and a detachable point having a socket in its base portion receiving

the second member, said detachable point also having notches to receive the lugs on 10 the first member and spring respectively.

In testimony whereof I affix my signature.
EMIL BOJKO.
